UNITED STATES PATENT OFFICE.

MICHAL FILIP, OF JERSEY CITY, NEW JERSEY.

DESIGN FOR A CUSPIDOR.

41,934.

Specification for Design.

Patented Nov. 21, 1911.

Application filed April 20, 1911. Serial No. 622,423. Term of patent 14 years.

To all whom it may concern:

Be it known that I, MICHAL FILIP, a subject of the Emperor of Austria-Hungary, residing at Jersey City, in the county of Hudson and State of New Jersey, have invented a certain new, original, and ornamental Design for a Cuspidor, of which the following is the specification, reference being had to the accompanying drawing, forming a part thereof.

The figure is a perspective view of the cuspidor, illustrating my new design.

I claim:

The ornamental design for a cuspidor, as shown.

MIKE FILIP.

Witnesses:

VICTOR WILUSZ,
CHRISTINA T. HOOD.
